UNITED STATES PATENT OFFICE

SIEGFRIED BEHR, OF NEW YORK, N. Y.

DESIGN FOR A CARD HOLDER OR SIMILAR ARTICLE

Application filed May 6, 1929. Serial No. 31,103. Term of patent 3½ years.

To all whom it may concern:

Be it known that I, SIEGFRIED BEHR, a citizen of the United States, residing at 5 West 30th St., New York city, in the county of New York and State of New York, have invented a new, original, and ornamental Design for a Card Holder or Similar Article, of which the following is a specification, reference being had to the accompanying drawing, forming part thereof.

Fig. 1 is a perspective front view of my card holder or similar article.

Fig. 2 is a perspective rear view of my card holder or similar article.

I claim:

The ornamental design for a card holder or similar article, substantially as shown.

SIEGFRIED BEHR.
